STEAM GENERATOR

Nils Gustave Sandstrom, Erie, Pa., assignor to
 Erie City Iron Works, Erie, Pa., a corporation
 of Pennsylvania

Application December 19, 1939, Serial No. 309,996

8 Claims. (Cl. 122—347)

This invention embodies an improvement in steam generators of the longitudinal drum, vertical water tube type. The generator is self-contained and provides a water cooled furnace, and is provided with a self-contained case. This includes a furnace having a combustion chamber and a convection chamber which are preferably separated by a bridge wall, the convection chamber being filled with water tubes extending from a longitudinal upper steam and water drum, extending the full length of the furnace to a lower drum, the lower drum terminating at the front end of the convection chamber.

The invention involves a system of water tubes forming the walls of the combustion chamber, these tubes being arranged in a downcomer bank and an upcomer bank, the downcomer bank being outside the upcomer bank of tubes. These inner and outer sets of tubes lead to a header extending along the sides of the combustion chamber at or near the bottom, and these two banks provide a circulation originating and terminating in the water space of the upper steam and water drum. The downcomer tubes lead from a portion of the upper drum separated from the main body thereof so that the circulation may be more definitely controlled.

One of the major features of the invention is this arrangement of the water wall for the combustion chamber. Other features and details of the invention will appear from the specification and claims.

A preferred embodiment of the invention is illustrated in the accompanying drawings as follows:

Fig. 1 shows a central vertical section of one modification of the boiler on the line 1—1 in Fig. 2.

Fig. 2 shows at its left side a section on the line 2—2 in Fig. 1, and at its right side a section on the line 2a—2a in Fig. 1.

Fig. 3 shows a section on the line 3—3 in Figs. 2 and 4.

Fig. 4 shows a side elevation of the lower part of the combustion chamber wall including clinker chills.

Fig. 4a a section on the line 4a—4a in Fig. 2.

Fig. 5 a central section of a modification, the modification being adapted to burn fine or liquid fuel, the section being on the line 5—5 in Fig. 6.

Fig. 6 a section on the line 6—6 in Fig. 5.

Fig. 7 a central section of a modification designed to accommodate an inclined stoker.

Fig. 8 a detached view showing the cooling tubes arranged on the bridge wall.

In the modification shown in Fig. 1, 1 marks an upper drum, 2 a lower drum, 3 a combustion chamber, 4 a bridge wall, 5 a convection chamber separated from the combustion chamber by the bridge wall. Water tubes 6 connect the upper and lower drums and practically fill the convection chamber.

The side walls of the convection chamber has a refractory 7 of ordinary form which is continued over the upper drum by insulation 8 in the usual manner. The side refractory 7 and insulation 8 is supported by a steel structure 9. A steel casing 10 is arranged at the side of the insulating material and this is supported and included in a general frame of structural steel 11.

A baffle 12 formed of refractory material is arranged along one bank of tubes giving a down-pass at the entrance of gases to the convection chamber. Baffles 13 and 14 of steel are provided at the rear of the convection chamber giving an up and down pass to the gases. The gases are discharged through a gas outlet 15 which is arranged at the side of the upper drum.

The combustion chamber is provided at each side with a water wall. This is accomplished by downcomer tubes 16 extending from the upper drum. The inlets of these downcomer tubes are separated from the main portions of the drum by a baffle plate 17. The lower ends of the tubes 16 lead to a header 18, and upcomer tubes 19 extend from the header in the furnace side wall to the water space of the upper drum. The tubes 19 are backed up by refractory blocks 20 and insulation 22. Channel iron lower blocks 21 are for chilling the clinker at the sides of the furnace.

Insulation 22 encloses the downcomer tubes 16 and the steel case 10 extends over the insulation in a manner similar to that of the convection chamber and is supported by the surrounding frame 11. It will be understood that the water wall is duplicated at both sides of the combustion chamber.

The front wall 23 of the combustion chamber is of refractory material and here again the case 10 extends outside of the wall and the frame for the casing supports the front end of the upper drum, and has a furnace opening 24 through which the furnace is fired.

The water level is maintained at substantially the medial line of the upper drum and steam outlets are taken through nozzles 25 and 26.

The water is fed through opening 27.

The independent circulating system forming the walls of the combustion chamber take water

from the upper drum which is comparatively clean so that the headers 18 are subjected to almost no accumulation of sediment. The distribution of this circulation throughout the length of the combustion space is very uniform, the flow resistances and freedom of circulation being exactly the same for all the tubes throughout the system. This rapidity or freedom of circulation assures practically water filled tubes throughout the system, thereby extending the life of the tubes and promoting their efficiency.

The circulation in the convection chamber is generally downward at the rear of the convection chamber and upward at the forward portion of the convection chamber where the tubes meet the incoming hotter gases. The system lends itself very well to an integral or self-contained generator unit.

In Figs. 5 and 6, 31 marks an upper drum, 32 a lower drum, 33 a combustion chamber, 34 a convection chamber, 35 a bridge wall, the bridge wall being extended forming a roof 36 of the forward end of the furnace. The front wall 37 of the furnace has an opening 38 for the introduction of fuel. Water tubes 39 connect the upper and lower drums. The water wall at each side of the combustion chamber is formed by the downcomer tubes 40 and upcomer tubes 41 leading from and to the upper drum and connecting it with a header 42 extending the full length of the setting. The end wall of the combustion chamber has the downcomer tubes 43a and upcomer tubes 44a leading from and to the water space of the upper drum and connecting it with a cross header 42a. These water walls are otherwise insulated and encased as in the structure shown in Fig. 1.

A cross header 43 extends across the end wall 37 and cooling tubes 44 extend along the furnace arch 36 and over the lower part of the bridge wall to the lower drum, thus effecting a cooling circulation along the arch and bridge wall. Header 43 is fed by tubes 45 connecting to the lower drum 32.

The convection chamber is baffled as in Fig. 1, and the water circulation and steaming characteristics are similar to those in Fig. 1.

The modification shown in Figs. 7 and 8 comprises an upper drum 47, a lower drum 48, combustion chamber 49, convection chamber 50, a front wall 51 having a stoker opening 52 and an inclined stoker 53.

The water wall of the combustion chamber is formed of tubes 54 and 55 which extend from the upper drum to a header 56 along the sides of the combustion chamber. This water wall is similar to that of Fig. 1 and similarly insulated and encased.

A bridge wall 57 separates the combustion and convection chambers and this wall extends below the lower drum. Tubes 58 and 59 extend from the lower drum through and along the lower part of the bridge wall to a cross header 60. The cross header is connected by tubes 61 with the lower drum 48.

The furnace, as a whole, is encased and insulated substantially as in the structure shown in Fig. 1, and the circulation and steam generation follows the same general plan.

By placing the upcomer tubes as well as the downcomer tubes in the upper drum to the water space, the agitation at the water level is decreased so that the steam discharged may carry less moisture. Also by connecting the upcomer tubes from the cross headers at the front below the water level, this also assists in reducing the

agitation and consequently provides a drier steam. To the same end the circulation from the cross header at the arch or bridge wall is returned to the lower drum and therefor the agitation with relation to this circulation is removed from the upper drum and tends to reduce the agitation.

It will be noted, however, that the entire heat exchange is carried into the liquid in its circulation, also the circulation is definitely controlled so that the steam gradually generated approaches the portion of the upper drum over the combustion space. What I claim as new is:

1. In a steam generator, the combination of a furnace having side walls; an upper steam and water drum extending longitudinally and horizontally along the top of the furnace; a lower water drum shorter than the upper drum providing furnace space under the upper drum and at the end of the lower drum; circulating tubes connecting the drums; and headers along the sides of the furnace wall, each side having an inner and outer set of circulating tubes connecting the headers and the water space of the upper drum, the inner tubes cooling the walls, the outer set of circulating tubes being embedded in the wall.

2. In a steam generator, the combination of a furnace having side walls and comprising a combustion chamber and a convection chamber; an upper steam and water drum extending longitudinally and horizontally along the top of the combustion and convection chambers; a lower water drum in the convection chamber; circulating tubes connecting the upper and lower drums in the convection chamber; headers along the side walls of at least the combustion chamber; and an inner and outer set of circulating tubes connecting each header and the water space of the upper drum, each inner set of tubes cooling the side wall, the outer set of circulating tubes being embedded in the wall.

3. In a steam generator, the combination of a furnace having side walls and comprising a combustion chamber and a convection chamber; a longitudinally extending upper steam and water drum in the combustion and convection chambers; a lower water drum in the convection chamber; circulating tubes connecting the upper and lower drums in the convection chamber; headers along the side walls of at least the combustion chamber; inner and outer sets of circulating tubes connecting each header and the water space of the upper drum, each inner set of tubes cooling the side wall; a cross header below the lower drum; tubes extending from the lower drum adjacent the combustion chamber to the cross header; and tubes connecting the cross header with the lower drum.

4. In a steam generator, the combination of a furnace having side walls, said furnace comprising a combustion chamber and a convection chamber, said chambers being separated by a bridge wall; a longitudinally extending upper steam and water drum in the combustion and convection chambers; a lower water drum in the convection chamber; tubes in the convection chamber connecting the upper and lower drums; headers along each side wall of at least the combustion chamber; an inner and outer set of tubes connecting each header with the water space of the upper drum, the inner tubes of each set cooling the side wall; a cross header to the rear of the combustion chamber; bridge wall cooling tubes connecting the lower drum with the cross header; and tubes connecting the cross header with the lower drum.

5. In a steam generator, the combination of a

furnace comprising a combustion space, a convection space, side and end walls, and a furnace arch below the convection space; a longitudinally extending upper steam and water drum in the combustion and convection spaces; a lower water drum above the arch in the convection space; tubes in the convection space connecting the upper and lower drums; a cross header adjacent the outer end of the arch; cooling tubes extending from the lower drum along the arch to the cross header; and tubes connecting the cross header with the lower drum.

6. In a steam generator, the combination of a furnace comprising a combustion space, a convection space, side and end walls, and a furnace arch below the convection space; a longitudinally extending upper steam and water drum in the combustion and convection spaces; a lower water drum above the arch in the convection space; tubes in the convection space connecting the upper and lower drums; a cross header adjacent the outer end of the arch; cooling tubes extending from the lower drum along the arch to the cross header; tubes connecting the cross header with the lower drum; headers along each side wall of the furnace; and an inner and outer set of tubes connecting each header with the water space of the upper drum, the inner tubes cooling the side wall.

7. In a steam generator, the combination of a furnace comprising a combustion space, a convection space, side and end walls, and a furnace arch below the convection space; a longitudinally extending upper steam and water drum in the combustion and convection spaces; a lower water

drum above the arch in the convection space; tubes in the convection space connecting the upper and lower drums; a cross header adjacent the outer end of the arch; cooling tubes extending from the lower drum along the arch to the cross header; tubes connecting the cross header with the circulating system of the generator away from the upper drum; headers along each side wall of the furnace; an inner and outer set of tubes connecting each header with the water space of the upper drum, the inner tubes cooling the side wall; a cross header along the outer wall of the combustion space; and an inner and outer set of tubes connecting the last-mentioned cross header with the water space of the upper drum, the inner set of tubes cooling the end wall of the combustion space.

8. In a steam generator, the combination of a furnace having side walls and comprising a combustion and convection space, the combustion space having a rear wall topped with a bridge wall; a longitudinally extending upper steam and water drum in the combustion and convection spaces; a lower drum in the convection space; tubes connecting the upper and lower drums; headers along the side wall; an inner and outer set of tubes connecting each header and the water space of the upper drum, the inner tubes cooling the side wall; a cross header to the rear of the combustion space; cooling tubes extending from the lower drum along the rear wall to the cross header; and tubes connecting the cross header to the lower drum.
